OR D 13,513

No. 13,513

JAN 9, 1883

UNITED STATES PATENT OFFICE.

II. CLAY BASCOM AND FRANCIS RITCHIE, OF TROY, NEW YORK, ASSIGNORS
TO N. S. VEDDER PATTERN WORKS, BASCOM, GALBRAITH & CO., OF
SAME PLACE.

DESIGN FOR A STOVE.

SPECIFICATION forming part of Design No. 13,513, dated January 9, 1883.

Application filed November 17, 1882. Term of patent 7 years.

To all whom it may concern:

Be it known that we, H. CLAY BASCOM and FRANCIS RITCHIE, each a citizen of the United States, residing in the city of Troy, in the 5 county of Rensselaer and State of New York, have jointly invented and produced a new and original Design for Stoves, of which the following is a specification, reference being had to the accompanying cut, print, or engraving 10 of a stove having said new design.

The design for the vase A consists of the upwardly-swelling top *a*, base *b*, and upwardly-tapering convexly-curved body *c*, having the cruciform ornament *d*, surrounded by the 15 four-arc molding *e*, all shaped and arranged so as to appear substantially as shown in the aforesaid print.

The design for the top B consists of the series of open pointed arches *f* along the outer 20 molding, *f'*, the two compound open-work end ornaments *g*, having the curved borders *g'*, and the intermediate cross-bar open-work part, *h*, all shaped and arranged together substantially as shown in the aforesaid cut.

The design for the plate ornament C consists of the raised, oblong, quadrilateral, round-cornered panel *i*, having projecting obtuse angles *i'* in its long sides and acute angles *i''* in its short sides, which angles are connected by 30 lines that with the angles form a lozenge having in its obtuse angles the ornaments *j*, and an intermediate name-space, *j'*, all shaped and arranged substantially as represented in the accompanying engraving.

The design for the compound corner ornaments, D, consists of the inner oblong ovate ornament, *k*, and the two lateral ornaments *l l*, having the straight outer sides, *l' l'*, meeting in an angle, the concave inner sides, *l''*, converging toward said angle, and the outer flaring three-pointed ends, *l'''*, all shaped, ornamented, and arranged substantially as represented in the aforesaid cut.

The design for the front plate, E, consists of 45 the central ornament C, composed of the parts *i i' i'' j j'*, as above described, in combination with the four corner ornaments, D, consisting of the parts *k l l' l'''*, as above specified, and all shaped and arranged substantially as shown 50 in the aforesaid engraving.

The design for the door or panel F consists of the compound central ornament M, in com-

bination with the corner ornaments, D, all composed, shaped, and arranged together substantially as represented in the aforesaid print. 55

The design for the front door, G, consists of the outwardly-curved upper part, *N*, having the ornamental border *o*, mica light-apertures *p*, and intervening ornaments *q*, in combination with the lower upright portion, *R*, having 60 the draft-openings *s*, intervening ornaments *t*, and top ornaments, *u*, all shaped and arranged together substantially as shown in the aforesaid cut.

The design for the legs consists of the body 65 *v*, having the border *w*, and the ornament *x*, having the downwardly-converging sides *y*, and ornamented four-pointed top *z*, all shaped and disposed substantially as shown in the aforesaid print. 70

What we claim as our joint invention is—

1. The design for the vase A, composed of the parts *a b c d e*, shaped and arranged together as set forth.

2. The design for the top B, composed of the 75 parts *f f' g g' h*, shaped and arranged together as set forth.

3. The design for the plate ornament C, composed of the parts *i i' i'' j j'*, all shaped and arranged together as set forth. 80

4. The design for the corner ornaments, D, composed of the parts *k l l' l'''*, shaped and arranged together as described.

5. The design for the plate E, consisting of the central ornament C and corner ornaments, 85 D, each composed and all arranged together as set forth.

6. The design for the door or panel F, consisting of the central compound ornament M and four corner ornaments, D, each composed 90 and all arranged together as described.

7. The design for the front door, G, composed of the parts *N o p q* and *R s t u*, all shaped and arranged as described.

8. The design for the legs, consisting of the 95 parts *v w x y z*, all shaped and arranged as set forth.

In testimony whereof we hereunto set our hands, in the presence of two subscribing witnesses, this 14th day of November, 1882.

II. CLAY BASCOM.
Witnesses: FRANCIS RITCHIE.
